UNITED STATES PATENT OFFICE.

JOHN COLEMAN AND HENRY MOORE, OF ST. LOUIS, MISSOURI.

ATTACHMENT FOR WATER-CLOSET BOWLS.

SPECIFICATION forming part of Letters Patent No. 655,688, dated August 14, 1900.
Application filed February 23, 1900. Serial No. 6,154. (No model.)

To all whom it may concern:

Be it known that we, JOHN COLEMAN and HENRY MOORE, citizens of the United States, residing at St. Louis, in the State of Missouri, have invented certain new and useful Improvements in Attachments for Water-Closet Bowls; and we do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to improvements in an attachment for water-closet bowls; and it consists in the novel arrangement, construction, and combination of parts, as will be more fully hereinafter described, and set forth in the claims.

20 One object of this invention is to construct a device to be attached to the bowl of a water-closet which will provide a water and sewer-gas tight joint by means of its adjustable connection.

25 Another object is the relation of the device to the bowl for preventing said bowl from becoming broken by the sinking of the floor or settling of the building, which is of common occurrence.

30 Referring to the drawings, Figure 1 is a side elevation of our complete device detached from the bowl. Fig. 2 is a vertical sectional view of the same, taken approximately through the center. Fig. 3 is a horizontal sectional view taken approximately on the line *a a* of Fig. 2.

In the construction of the device, as shown, we provide a cylindrical tube 1, which is in any desirable manner connected to the horn of the bowl of a water-closet and is provided at its one end with a projecting flange 2. Below the flange and formed integral therewith is an extension 3 of thinner material than the tube proper and adapted to be fitted into a rubber spud 4, its purpose being fully hereinafter set forth. The rubber spud 4 is provided at its upper end with a projecting flange 5, which is to singly fit against the under surface of the flange 2 and the upper surface of the threaded nipple 6 and are each securely held together by a threaded cap 7. (See Fig.

2.) The cap 7 has at its upper end an inwardly-projecting flange 8, which seats against the upper surface of the flange 2. The nipple 6 is formed integral with a cylinder 9 of larger circumference and extending downwardly to any desired length. In this cylinder is placed the horn 10, provided in its inner surface with a plurality of grooves 11. In this horn, attached to bowl, is held the rubber spud by means of a metallic ring 12, acting as a spring, its tendency being to press the rubber spud within the groove 11 in the manner as shown in Fig. 2, thereby tightly holding the same therein and causing a tight joint. The ring 12 is constructed, as shown in Fig. 3, with its ends lapping each other and formed at their extremities into inwardly-bent hooks. The normal tendency of the spring is to open to a larger diameter, which causes a perfect joint by pressing the rubber into the groove 11 of the horn; but by inserting a suitable tool between the hooks and moving them away from each other the lapping ends are caused to slide over each other, which reduces the diameter of the ring, as is necessary in removing or inserting the rubber within the horn. Said tool is introduced from the upper end of the device shown in Fig. 2 and the cap or coupling 7 is applied later.

The arrangement of the parts coming in contact with the flanged end of the spud produces a perfect water and gas tight joint, and by the use of said spud in this connection the horns of the water-closet bowls are prevented from breaking or cracking which is caused by the settling of buildings.

Having fully described our invention, what we claim, and desire to secure by Letters Patent, is—

1. The combination with the horn of a water-closet bowl having a plurality of interior annular grooves; of a rubber spud entering said horn, an expansible ring within the spud and distending it normally into one of said grooves, the ends of the ring lapping each other and their extremities formed into hooks, and a metallic tube coupled to the projecting end of said spud, substantially as described.

2. The combination with the horn of a water-closet bowl having an interior annular groove; of a rubber spud entering said horn,

an expansible ring within the spud having its extremities turned inward toward the axis thereof, a threaded nipple around the outer end of the spud and having a cylinder surrounding said horn, a tube against the end of the spud, and a coupling between said tube and nipple, substantially as described.

In testimony whereof we affix our signatures in presence of two witnesses:

JOHN COLEMAN.

HENRY MOORE.
